UNITED STATES PATENT OFFICE.

JAMES O. REYNOLDS, OF EVANSVILLE, INDIANA.

COMBINED HAND AND BENCH VISE.

1,262,389.

Specification of Letters Patent. Patented Apr. 9, 1918.

Application filed June 12, 1917. Serial No. 174,234.

To all whom it may concern:

Be it known that I, JAMES O. REYNOLDS, a citizen of the United States, residing at Evansville, county of Vanderburg, and

5 State of Indiana, have invented certain new and useful Improvements in Combined Hand and Bench Vises, of which the following is a specification.

This invention relates to combination 10 hand and bench vises.

One object of my invention is the provision of a combined hand and bench vise comprising a clamp of improved construction adapted to be applied to a bench or 15 table, and a vise adapted to be detachably engaged with the clamp, whereby the hand vise may be used alone, or, it may be quickly and easily attached to the clamp and used as a bench vise. In that connection, I provide 20 improvements in the clamp, and a hand vise having a novel construction of jaw adapted to directly, and detachably, engage or interlock with the clamp to form a secure connection therebetween without interfering 25 with the operation of the vise.

Another object of the invention is the provision of a novel vise embodying jaws, a wedge plate, shank, and thumb screw, constructed and combined in a novel manner 30 whereby the jaws may be set at an angle to admit and hold tapering materials, or, can be arranged with their gripping faces parallel to hold square stock. Furthermore, these improvements provide for an adjustable fulcrum for the jaws which, combined 35 with the handle for adjusting the wedge plate, and the clamping thumb screw, provides a compound leverage on the jaws, resulting in a more powerful grip on the material being held than with the old style of 40 jaws.

The invention embodies further improvements and novel combination of parts appearing more fully hereinafter and shown 45 in the accompanying drawings. The disclosure of the invention is to be considered as illustrative, rather than restrictive, of the scope thereof, as modifications may be resorted to without departing from the essential principles of the device.

50 In the accompanying drawings:—

Figure 1 is a side elevation showing the device used as a bench vise;

Fig. 2 a vertical section on line 2—2

55 Fig. 1;

Fig. 3 a vertical section, taken at right

angles to Fig. 2, showing the jaws, wedge, and adjusting screws;

Fig. 4 an edge view looking toward the clamp;

Fig. 5 a plan view thereof;

Fig. 6 a detail edge view of the wedge and the cup;

Fig. 7 a side elevation partly in section of the device ready for use as a hand vise 65 and for holding tapered stock;

Fig. 8 a similar view, the handle being broken away and the jaws arranged for holding stock which tapers downwardly;

Fig. 9 a side elevation of one of the jaws; 70

Fig. 10 a cross section on line 10—10 Fig. 8; and

Fig. 11 a detail of the shank or stem.

My invention may be used as a hand vise, or, as a bench vise. It is shown arranged 75 for use as a bench vise in Figs. 1 and 2 and comprises, generally, a clamp 1 and a vise 2. The clamp 1 has a thumb screw 3 provided with a ball-swiveled head 4 adapted to be pressed against the bench 5 to hold the 80 clamp 1 thereon. The vise 2 is attachable to, or detachable from, the clamp 1. To enable the clamp and vise to be quickly and easily combined, or, disconnected, there is provided in the clamp a vertical slot 6 which 85 tapers from its upper end 7 to its lower end 8. The slot is undercut or dovetailed as shown at 9. A channel or slot 10 runs from the lower face of the clamp into the lower end portion of the slot 6. 90

The vise has a pair of jaws 11 which are substantial duplicates. They are provided with inclined slots 12 in their inner faces and have seats or concavities 13 below their tops. One of the jaws is screw-threaded at 95 14 and the other has a plain aperture 15 and is provided on its outer face with concavity 16. A thumb screw 17 has its blank portion 18 passing freely through the opening 15 and its screw-threaded portion 19 engaged 100 with the screw-threads 14. By turning this screw the jaws may be advanced toward each other. The thumb-screw has a rounded portion 20 which is received in the concavity or seat 16 and the inner face of the jaw 105 has an enlarged concavity 21 beyond the seat 13, to permit the jaw 11 to tilt, as will hereinafter appear.

A shank or stem 22 which has a screw-threaded part 23, has a head 24 provided 110 with concavities 25, 26, in its opposite sides and an opening 27 extending therethrough

which receives the thumb-screw 17. Coil springs 28, 29 surround the thumb-screw 17 and have their ends seated in the respective concavities or seats 13 and the concavities 25, 5 26. These springs, by their tendency to expand, press the jaws 11 apart, when permitted by the un-screwing of the thumb-screw 17.

Slidable on a blank portion of the shank 10 or stem 22 is a wedge plate 30 whose edges 31 slope upwardly and are received in the slots or channels 12 of the jaws. The wedge plate is provided with a tubular central portion 32 where it is slidably mounted on 15 the blank portion of the shank 22. In the lower edge of the wedge plate 30 is a cut-out portion 33 in which is received a cup 34. The handle 35 is provided with a ferrule 36 which is fastened thereto at 37 and has 20 internal screw-threads 38 engaged with the screw-threaded portion 23 of the shank 22. The handle 35 is hollow to permit the free entry of the screw-threaded part 23 thereto. A spring 39 surrounds the stem 22 and 25 is seated in the cup 34 and in a concavity 40 in the upper face of the ferrule or nut 36. The tension of the spring 39 need only be 30 sufficiently strong to support the wedge plate 30 and keep it from falling down. The adjustment of the wedge plate up and down 35 on the blank portion of the shank 22 is accomplished by turning the handle 35 while holding the jaws in the hand. By turning the handle 35 in one direction, there is a 40 tendency to compress the spring 39 and consequently the adjustment is transmitted through the spring to the wedge plate, elevating it. The reverse turning of the handle 35 relieves the tension on the spring 39 and 45 the wedge plate will then descend by gravity. The purpose of changing the position of the wedge plate 30 is to vary the point of application of the fulcrums 41 to the jaws 11 to thereby increase or diminish the gripping action of the jaws on the piece of work 50 being held by them. Furthermore, the adjustment of the wedge plate accomplishes a spreading, wedging, action on the jaws and intensifies the gripping action so that a compound gripping action is obtained by the use of the wedge plate and its adjusting 55 means in connection with the gripping action had by turning the thumb-screw 17. Another important result obtained is that,

according to the position of the wedge plate 55 and the arrangement of the thumb-screw 17, the jaws can be so arranged that their gripping faces will be inclined, or converge either downwardly, or upwardly, adapting them to evenly grip tapered material, as 60 shown in Figs. 7, 8.

The jaws 11 are tapered from their upper to their lower ends, as shown in Fig. 9 corresponding to the taper from 7 to 8 in the clamp 1. Consequently, either one of the 65 jaws can be inserted in the slot 6 and the vise will then be securely held by the clamp 1, adapting the device for use as a bench vise. The edges of the jaws are beveled or chamfered at 42 to facilitate quick and easy entry 70 of the jaw into the slot 6. The slot 10 provides clearance for the edge of the wedge plate 30, when the latter is adjusted downwardly beyond a given point.

The device may be used as a bench vise as 75 shown in Figs. 1, 2, or, as a self-contained hand vise as shown in Figs. 7, 8.

Having thus described my invention, what I claim as new and desire to secure by Letters Patent is:—

1. In a vise, the combination with tilttable jaws each having a slot, of a screw threaded shank or stem, a handle which carries said shank or stem, said handle and stem being relatively adjustable, a wedge plate slidably 85 carried on the stem and having inclined edges received in the slots of the respective jaws, a spring carried by the stem between the handle and the wedge plate, and means for contracting and expanding the jaws in 90 relation to each other.

2. In a vise, the combination with tilttable jaws, of a screw-threaded shank or stem, a thumb-screw passing through the shank or stem adapted to contract the jaws, spring 95 means for expanding the jaws, a wedge plate slidable on the stem, a rotatable handle having a ferrule or nut engaged with the screw-threaded part of the shank or stem, and a spring interposed between the handle and the wedge plate, said wedge plate being adapted to spread the jaws and to exert, in connection with the thumb-screw, a compound gripping action of said jaws.

In testimony whereof, I hereunto affix my 105 signature.

JAMES O. REYNOLDS.
